CASING FOR FALSE ALARM DETERRENT

Sidney J. Jacoby, 601 W. Susquehanna,
Philadelphia, Pa. 19122

Filed July 15, 1966, Ser. No. 3,085

Term of patent 14 years

(Cl. D72—1)

FIG. 1

FIG. 2

FIG. 6

FIG. 3

FIG. 4

FIG. 5.

FIG. 1 is a perspective view of a casing for false alarm deterrent, showing my new design.

FIG. 2 is a front elevational view thereof.

FIG. 3 is a left elevational view thereof.

FIG. 4 is a right side elevational view thereof.

FIG. 5 is a top plan view thereof.

FIG. 6 is a bottom plan view thereof.

The broken line representation of a fire alarm box in FIG. 1 is for purposes of illustration only.

I claim:

The ornamental design for a casing for false alarm deterrent, as shown and described
